LEVELING MACHINE

Erastus E. Winkley, Lynn, Mass., assignor to
United Shoe Machinery Corporation, Flemington,
N. J., a corporation of New Jersey

Application March 22, 1941, Serial No. 384,717

31 Claims. (Cl. 12—34)

This invention relates to machines for shaping or leveling the bottoms of shoes, and is herein illustrated as embodied in a leveling machine of the type disclosed in Letters Patent of the United States No. 2,230,244, granted February 4, 1941, upon an application filed in the names of F. V. Hart and J. J. Austin. It is to be understood, however, that in its more general aspects the invention is not limited to machines of the particular type illustrated.

Machines of the above-mentioned type comprise in their organization a leveling tool, such as a spring-pressed roll, a shoe support which is adjustable to accommodate shoes of different sizes, and power-operated means which is continuously under control of the operator for imparting to the shoe support swinging movements in opposite directions lengthwise of a shoe thereon to cause the leveling roll to operate progressively along the shoe bottom. Such machines are also provided with other power-operated means also continuously under control of the operator for imparting to the leveling roll tipping movements in opposite directions laterally of the shoe to vary its inclination in operating upon the opposite marginal proportions of the shoe bottom, a hand lever being provided for controlling each of the above-mentioned power-operated means. By means of the appropriate hand lever the operator is enabled to start, stop or reverse the swinging movement of the shoe support or the tipping movement of the leveling roll and to determine variably, by the extent of movement of the hand lever in either direction, the extent of rearward or forward swinging movement of the shoe support or the extent of tipping movement of the leveling roll in one direction or the other laterally of the shoe. In the use of the machine, for example on shoes of a style characterized by a pronounced line or ridge across the sole at the ball line, it is necessary for best results that the movements of the shoe support be controlled with such accuracy as to cause the sole to be leveled only up to such a line or ridge so as to accentuate it. While such a machine is under substantially as full control of the operator as if he were operating it manually, it is sometimes difficult to determine the exact point in the operation of the roll on the shoe bottom at which to stop the swinging movement of the shoe support so as to insure such results while preventing the roll from obliterating such a line or ridge.

An object of the present invention, accordingly, is to provide in a machine of the above-

mentioned type means for automatically terminating the movement of the shoe support in either direction lengthwise of the shoe each time in the operation of the machine when the leveling roll is located nearly at the junction of the forepart and shank portions of the shoe bottom. For the purposes in view, the construction shown comprises a stop movable by the shoe support and a member or plate having formed thereon spaced shoulders, one of which is arranged by engagement with the stop to prevent movement of the shoe support in one direction beyond a position in which the leveling roll is located substantially at the junction of the forepart and shank portions of the shoe bottom and the other shoulder of which is arranged by engagement with the stop to prevent movement of the shoe support in the opposite direction beyond a position in which the leveling roll is nearly in the same location on the shoe bottom. Machines of the type illustrated in the above-mentioned Letters Patent also include in their organization means enabling the operator at will to cause the lifting of the leveling roll from engagement with the shoe, and in accordance with a further feature such means is utilized to operate means for moving the movable stop out of operative relation to either one of the above-mentioned shoulders to permit movement of the support beyond the position determined by that shoulder. Preferably, as shown, the shoulders are so shaped as to vary the extent of swinging movement of the shoe support in accordance with variations in length of the forepart and shank at the opposite sides of the shoe bottom, and novel mechanism is provided for moving the plate relatively to the movable stop in opposite directions in response to the tipping movements of the leveling roll in opposite directions, this mechanism comprising connections that are adjustable by the operator to cause the plate to be moved in the same direction for operating upon either the inside or the outside marginal portions of both left and right shoes.

In a further aspect, the invention provides novel means for preventing movement of the shoe support in a rearward direction in operating on the forepart beyond a position in which the leveling roll is located substantially at the junction of the forepart and shank, which means is adjustable to vary the extent of such rearward movement in accordance with variations in length of the foreparts of shoes of different sizes and styles. As herein illustrated, the movable stop is connected to the shoe support in

such manner that its initial position relative to the above-mentioned plate is varied in accordance with variations in length of the foreparts of shoes of different sizes in response to adjustment of the shoe support to accommodate shoes of different sizes. The connections are further such that they may be adjusted independently of the size adjustment of the shoe support to cause the movable stop to be moved relatively to the plate at different rates of speed to vary the extent of rearward movement of the support in accordance with variations in length of the foreparts of shoes of different styles.

The above and other features of the invention including various novel details of construction and combinations of the parts will now be more particularly described by reference to the accompanying drawings and pointed out in the claims.

In the drawings,

Fig. 1 is a view in side elevation of a machine of the type disclosed in the above-mentioned application with the present invention embodied therein;

Fig. 2 is a view in side elevation, on an enlarged scale, of a portion of the mechanism shown in Fig. 1, with parts broken away and with other parts in section;

Fig. 3 is an enlarged detail view in side elevation of a portion of the mechanism shown in Fig. 2;

Fig. 4 is an enlarged plan view of the mechanism shown in Fig. 3;

Fig. 5 is an enlarged plan view of a portion of the mechanism shown in Fig. 2;

Fig. 6 is a view in rear elevation, on an enlarged scale, of a portion of the mechanism shown in Fig. 2 with parts broken away and other parts in section;

Fig. 7 is a view partly in section on the line VII—VIII of Fig. 6;

Fig. 8 is a view partly in section on the line VIII—VIII of Fig. 2; and

Fig. 9 illustrates the relation of the leveling roll to the shoe at the limit of rearward movement of the shoe-supporting jack when the roll is operating on the forepart, and at the limit of forward movement of the jack when the roll is operating in the shank portion of the shoe bottom.

Since the invention is illustrated as applied to a leveling machine of the type fully shown and described in the above-mentioned Letters Patent, only such parts of the machine as it is necessary to refer to for an understanding of the invention are shown and will be described in detail. It will be understood that the machine includes in its organization a shoe support or jack 10 to which swinging movements are imparted by power-operated means, under control of the operator, to carry the shoe rearwardly and forwardly beneath a leveling roll 12 which is yieldingly forced down on the shoe bottom to apply leveling pressure progressively to the sole and to which tipping movements may be imparted by other power-operated means, also under control of the operator, to cause leveling pressure to be applied to the margins of the sole. The jack 10 (Fig. 1) comprises a toe post 14 and a heel post 16 which are pivoted together at 18 for relative adjustment for shoes of different sizes by means of a threaded rod 20, which moves the heel post toward or from the toe post so that the toe ends of shoes of different sizes will be presented initially in substantially the same

relation to the roll 12. The toe and heel posts are provided with means for supporting a last and shoe for the leveling operation, comprising an adjustable toe support 22 carried by the toe post 14 and a spindle 24 carried by the heel post 16, the spindle extending through an enlarged opening in a plate 26, also carried by the heel post, which plate is free to tip about an axis extending laterally of the shoe to adjust itself to the top face of the heel end of the last. The roll 12 is mounted for turning movement on a rod 28 carried by a holder 30, which is pivotally connected at 32 to a carrier 34 mounted for tipping movements laterally of the machine about the axis of a forwardly and rearwardly extending shaft 36 supported by bearings at the top of the frame of the machine.

In the illustrated machine the rearward and forward swinging movements of the jack 10, as a whole, about the axis of the shaft 36 and the tipping movements of the roll 12 laterally of the shoe are effected by power through the action of fluid-pressure means, which is not herein shown in detail since it may be and preferably is substantially like that fully shown and described in the previously mentioned Letters Patent. Briefly, the fluid-pressure means comprises two fluid motors 40 and 42 (Fig. 1), the motor 40 being connected to the jack 10 by means of a pinion 44, the teeth of which mesh with segmental teeth 46 formed on an arm 48 integral with the toe post 14, and the fluid motor 42 being geared to a shaft 50 on which there is fast an arm 52 having pivotally connected to it an upwardly extending adjustable rod 54 pivotally connected at its upper end to an arm 56 on the carrier 34. As fully disclosed in the above-mentioned Letters Patent, the machine is provided with valve mechanisms, one of which is shown at 58 (Fig. 1), that are movable in opposite directions by means of hand levers 60 and 62 respectively to control the flow of fluid to and from the upper and lower ends of the motors 40 and 42 and thus to control the direction of swinging movement of the jack 10 and the direction of tipping movement of the roll 12. Connections are provided between each motor and its associated valve mechanism for moving the valve mechanism to closed position to stop the swinging movement of the jack or the tipping movement of the roll when the movement of its associated hand lever is stopped, the construction being such that by means of the hand levers 60 and 62 the operator may control the direction and extent of swinging movement of the jack and of tipping movement of the roll as well as the speed of such movements.

Formed on the holder 30 is a rearwardly extending arm 64 (Fig. 1) connected by a short link 66 to the rearwardly extending arm 68 of a bell-crank lever 70 fulcrumed at 72 to the carrier 34. The bell-crank lever 70 has a pair of downwardly extending arms 74, carrying trunnions 76 extending into a circumferential groove 78 formed in a bushing 80 that is slidably mounted on the shaft 36. Pivotally mounted on a laterally extending shaft 82, supported by suitable bearings in the frame 84 of the machine is an upwardly extending arm 86, the upper portion of which is forked to straddle the bushing 80, the arms of the forked portion carrying trunnions 88 extending into a circumferential groove 90 in the bushing 80. Mounted on the shaft 82 is a downwardly extending yoke 92 and connected to this yoke by a threaded rod 94 is a yoke-shaped

member 96, between the arms of which at their lower ends there is pivoted a lever 98. The lever 98 has oppositely extending arms of equal lengths to the ends of which are pivotally connected abutments 100, 102 for relatively heavy expansion springs 104, 106. At its upper end the spring 106 bears against an abutment 108 pivoted at 110 to the frame 84. The spring 104 at its upper end engages an abutment 112 pivotally connected to an arm 114 integral with the arm 86. It will be evident that the springs 104, 106 tend to swing the arms 114, 86 in a clockwise direction, as viewed in Fig. 1, to cause the sleeve 80 to be moved rearwardly on the shaft 36 and thus to impart downward swinging movement to the holder 38 to lower the leveling roll 12, the initial position of which is determined by the engagement of the arm 86 with an adjustable stop, illustrated as a screw 116 threaded in the frame 84. The screw 116 is preferably so adjusted that the leveling roll 12 is maintained initially in a position lower than that which it occupies in operating upon the shoe and is lifted at a predetermined time in the first rearward swinging movement of the jack to prevent interference between the roll and the toe end of the sole. For thus lifting the roll 12 there is provided a plunger 118 and connections therefrom to the arm 86 for swinging the arm in a counterclockwise direction (Fig. 1) against the resistance of the springs 104 and 106. As shown, the plunger 118 is connected to the rearwardly extending arm of a lever 120 which is pivoted intermediate between its ends to a bracket 122 secured by screws 124 to the frame 84. The lever 120 has a forwardly extending arm to which there is pivotally connected an upwardly extending adjustable rod 126, connected at its upper end to an arm 128 integral with the arm 86.

For operating the plunger 118 to swing the lever 120 and the arms 128 and 86 in the direction to raise the leveling roll 12 to a level higher than the bottom of the shoe, there is provided a fluid motor 130 (Fig. 1), not herein shown in detail since it may be, and preferably is, substantially like that shown in the previously mentioned Letters Patent. In the illustrated machine the operating fluid, supplied by a pump, is maintained initially under a predetermined low pressure by means of a control valve indicated generally by the reference numeral 132, the control valve being held open by the pressure of the fluid against the resistance of a spring (not shown) to permit excess fluid to return to a reservoir in the base 85 of the machine. The pressure of the operating fluid, however, is sufficient at this time to impart rearward swinging movement to the shoe-supporting jack but insufficient to operate the fluid motor 130 to raise the leveling roll 12 against the resistance of the springs 104 and 106. As the shoe-supporting jack is swung rearwardly to carry the toe end of the shoe toward the leveling roll 12, the control valve spring is compressed by the swinging of a pair of toggle links 134, 136 (Fig. 1) into substantially parallel relation in response to the forward movement of a horizontal rod 138 which is slidably mounted in the frame 84 and is moved forwardly to thus operate the toggle links by means of a spring 139 (Fig. 2) in response to the rearward movement of the jack to carry the toe end of the shoe toward the leveling roll. Compression of the control-valve spring causes the pressure of the operating fluid to be increased sufficiently to operate the fluid motor 130 to raise the plunger 118

and, through the above-described connections, to swing the arm 86 in the direction to lift the leveling roll 12. Pinned to the rod 138 is a collar 140 (Fig. 2) and loosely mounted on the rod 138 is a second collar 142, to which there is pivotally connected the downwardly extending arm 144 of a lever 146 pivotally connected to the casting of the fluid motor 130. The lever 146 is connected by links 147 to a valve stem 148. The construction is such that after the toggle links 134, 136 have been moved into a substantially straightened condition in response to the forward movement of the rod 138 and substantially at the time in the first rearward movement of the jack when the toe end of the shoe is directly under the leveling roll 12, the lever 146, in response to continued forward movement of the rod 138, is swung by engagement of the collar 140 with the collar 142 in the direction to impart downward movement to the valve stem 148 to close a valve (not shown) and thereby to disconnect the fluid motor 130 from the source of pressure fluid to cause the leveling roll 12 to be released to the action of the springs 104, 106 for downward movement into engagement with the bottom face of the shoe at the toe end. Swinging movement of the toggle links 134, 136 into a substantially straightened condition is limited by engagement of an adjustable stop screw 150 (Fig. 1), carried by the link 134, with a bracket 152, and continued forward movement of the rod 138 thereafter is permitted by reason of the compression of a spring 153 (Fig. 2) on the rod 138 through which the toggle links are swung into substantially parallel relation. At its forward end the rod 138 is pivotally connected to an arm 154 (Figs. 1 and 2) which is fast to a shaft 156 fulcrumed in the frame 84. Fast to the shaft 156 is an upwardly extending arm 158 (Fig. 1) carrying a roll 160 that engages a downwardly extending arm 162 on the toe post 14 of the jack. Forward movement of the rod 138 is limited by the engagement of a pin 164 carried by a rearwardly extending arm 166 adjustably secured to the shaft 156 with an adjustable rod 168 at the upper end of a lengthwise slot 170 in the rod, the rod being pivotally connected at its lower end to a treadle 172 which is fulcrumed at 174 to the base 85. A spring 176 (Fig. 1) tends to uphold the treadle 172 with an adjustable screw 178 in the treadle in engagement with a portion of the base 85.

A spring 180 (Fig. 2) connected at one end to a pin (not shown) projecting from the frame 84 and at the other end to an upwardly extending arm 182 of the lever 146 tends to swing the lever in a direction to impart upward movement to the valve stem 148 and to hold the valve controlled thereby normally open with the fluid motor 130 connected to the source of pressure fluid. In the course of the operation of the machine, with the rod 138 in its forward position and with the above-mentioned valve closed, the operator may by depression of the treadle 172 move the rod 138 rearwardly far enough to release the lever 146 to the action of the spring 180 without moving the toggle links 134 and 136 into non-parallel relation, thereby causing the above-mentioned valve to be opened and the motor 130 to be connected to the source of pressure fluid to cause the lifting of the leveling roll 12 from engagement with the shoe.

For purposes of the present invention, the illustrated machine is provided with means for automatically terminating the movement of the jack

10 in a rearward direction in operating on the forepart and in a forward direction in operating in the shank, each time in the movement of the jack when the leveling roll 12 is located nearly at the junction of the forepart and shank portions of the shoe bottom. This means comprises, as herein shown, a forwardly and rearwardly extending horizontal rod 184 (Fig. 2), slidably mounted in bearings in the frame 84 and connected to the jack 10 to move therewith. The rod 184 carries a pin 186 which is arranged by engagement with the forward edge face 188 of a plate 190 which acts as a shoulder or abutment to limit rearward swinging movement of the jack and by engagement with the rear edge face 192 of the plate which serves as a shoulder or abutment to limit forward swinging movement of the jack. The connections between the rod 184 and the jack 10 comprise a sleeve 194 slidably mounted on the rod between a collar 196 pinned to the rod and a second collar 198 adjustably secured to the rod. Pivotally connected to the sleeve 194 is a block 200 through which extends the rear end portion of a forwardly extending rod 202, the rod 202 being held against endwise movement relatively to the block 200 by nuts 204 threaded on the rod and engaging the opposite end faces of the block. At its forward end the rod 202 is pivotally connected to a block 206, which is movable on a substantially vertical guideway 208 formed on a casting 210 which is pivotally connected at 212 to a block 214 loosely mounted on a reduced median portion of the threaded rod 20 and held against movement lengthwise of the rod 20 by collars 216 pinned to the rod and engaging the opposite end faces of the block 214. Extending through the block 206 is a threaded rod 218 rotatably mounted in the casting 210 and provided at its upper end with a hand wheel 220 for turning it to move the block 206 along the guideway 208 and thus to vary the position of the block 206 relatively to the block 214. At its lower end the casting 210 is pivotally connected to an arm 222, which is pivotally connected at 224 to the heel post 16 of the jack.

The rod 20 has left-hand and right-hand threaded end portions engaging trunnion blocks on the toe and heel posts 14 and 16, respectively, and formed on the forward end of the rod is a head 225 for turning the rod to adjust the heel post toward or from the toe post to accommodate the jack for different sizes of shoes. It will be understood that the block 214 will be located substantially midway between the toe and heel posts in all positions of adjustment of the heel post. As the jack is swung rearwardly to carry the toe end of the shoe under the leveling roll and then farther rearwardly to cause the roll to operate along the bottom of the forepart of the shoe, the sleeve 194 will act by engagement with the collar 198 to impart rearward movement to the rod 184 until the pin 186 engages the forward edge face 188 of the plate 190, thus limiting the rearward movement of the jack; the arrangement being such that when the pin 186 thus engages the plate 190 the roll 12 will be located substantially at the junction of the forepart and shank portions of the shoe bottom. Thereafter the jack may be swung forwardly, the rod 184 moving forwardly with the jack by reason of engagement of the sleeve 194 with the collar 196, and again rearwardly while the roll 12 is operating on the forepart; after which the operator may, by means hereinafter described,

move the pin 186 out of operative relation to the plate 190, to permit the jack to be swung rearwardly beyond the position determined by engagement of the pin with the edge face 188 of the plate and thus to bring the shank portion of the shoe into position beneath the leveling roll. With the pin 186 again in operative relation to the plate 190, the jack may be swung forwardly and rearwardly while the roll 12 is operating in the shank, the limit of forward movement of the jack being determined by engagement of the pin 186 with the rear edge face 192 of the plate 190. By reference to Fig. 2 it will be seen that the adjustable collar 198 on the rod 184 is preferably spaced from the sleeve 194 a distance somewhat less than the width of the pin 186 plus the width of the plate 190, so that the pin 186 by engagement with the rear edge face 192 of the plate will limit the forward movement of the jack while operating in the shank when the roll 12 is located nearly at the junction of the bottom of the shank and forepart; that is, in such relation to the junction of the shank and forepart as to cause the roll to level the sole up to the ball line without obliterating the ball line (Fig. 9).

In operating on shoes of different styles the operator may, by turning the hand wheel 220, vary the position of the block 206 relatively to the block 214 and the axis of the shaft 18, about which the jack as a whole is mounted to swing. Since the jack is swung at a uniform rate of speed, by this adjustment the pin 186 may be caused to move at different rates of speed to vary the extent of rearward swinging movement of the jack before the pin 186 engages the edge face 188 of the plate 190, in accordance with variations in the length of the foreparts of shoes of different styles. It will be readily seen that if the shoe is of a style in which the forepart and shank portions are of the same length, the block 206 will be adjusted along the guideway 208 so that its pivotal connection to the rod 202 will coincide with the pivot 212 of the block 214. For shoes of different sizes of that style adjustment of the heel post toward and from the toe post will vary the position of the pin 186 relatively to the plate 190 in accordance with the variations in length of the different sizes, since by turning the rod 20 the pin 186 will be moved toward or from the plate 190 substantially half the distance the heel post is swung toward or from the toe post. If, however, the shoe is of a style in which the forepart is longer than the shank portion and the block 206 has accordingly been adjusted to carry its pivotal connection to the rod 202 closer to the axis of the shaft 18 than the pivot 212 of the block 214 to the casting 210 and thus to cause a greater extent of swinging movement to be imparted to the jack before the pin 186 engages the plate 190, adjustment of the heel post alone toward or from the toe post will not vary the position of the pin 186 relatively to the plate 190 in accordance with variations in the length extensions of shoes of different sizes of that style. This is effected in the illustrated construction by imparting to the casting 210 a swinging movement relatively to the block 214 to vary the position of the pin 186 as the heel post is adjusted toward or from the toe post for different sizes. The casting 210 is thus swung by means of the arm 222 which, as previously pointed out, is pivotally connected to the heel post 16 and the casting 210, the construction being such that in operating upon shoes of dif-

ferent styles, that is, shoes in which the fore-parts are proportionately longer than the shank portions, the position of the pin 186 relatively to the plate 190 will be varied in accordance with variations in the length extensions of different sizes of shoes of each style.

Geared to the rod 184 is a vertically movable rack bar 226 (Fig. 2), connected by a link 228 to one arm of a lever 230 which is fulcrumed at 232 to the frame 84 and is provided with a second arm 234 connected by an adjustable rod 236 to one arm of a two-armed lever 238 fulcrumed at 240 to a bracket 242 which is secured to a bracket 244 in which the plunger 118 is slidably mounted. The second arm 246 of the lever 238 has pivotally connected to it a depending pawl 248 (Figs. 3 and 4) and engaging this pawl is a spring-operated pin 250 in the bracket 242, the pin acting normally to hold the pawl in engagement with a ratchet plate 252 which is vertically movable in a guideway 254 in the bracket 244 and is connected at its upper end to a plate 256 fast to the plunger 118. A spring 258 (Fig. 2) connected at one end to a pin 260 in a bracket 252 in which the rack bar 226 is slidably mounted and at the other end to a hook 264 which extends through a pin 266 in the arm 234 of the lever 230, tends to hold the parts in the positions shown in Fig. 2, with a pin 268 in the rack bar 226 in engagement with a finished surface 270 on the bracket 262 and with the pin 186 in a horizontal position and in operative relation to the plate 190. Pivotally connected to the bracket 242 at 272 is a lever 274 (Figs. 2, 3 and 4) carrying an adjustable screw 276 held in adjusted position by means of a nut and lock-nut 278. The lever 274 has a downwardly extending arm 280, the lower end of which lies in the path of movement of the above-mentioned rod 138. A spring 282, connected at one end to a hook 284 in the bracket 242 and at the other end to a pin 286 projecting from the lever 274, tends to swing the lever 274 in a clockwise direction, as viewed in Fig. 2, and to hold the lower end of its arm 280 in engagement with the rear end of the rod 138.

As previously pointed out, when the jack 10 is swung by power, under the control of the hand-lever 60, rearwardly from its initial shoe-receiving position, the rod 138 is moved forwardly to straighten the toggle links 134 and 136 and to cause the fluid motor 130 to raise the plunger 118 to elevate the leveling roll 12 into a position higher than it occupies in operating upon a shoe. As the toe end of the shoe is moved into position beneath the roll 12 the rod 138 is moved farther forwardly to cause the lever 146 to be swung in a direction to close a valve which disconnects the fluid motor 130 from the source of pressure fluid, thus releasing the leveling roll to the action of the springs 104, 106 for downward movement into engagement with the shoe bottom, the plunger 118 also moving downwardly at the same time as the roll 12. It will be understood that as the plunger 118 is moved upwardly to elevate the leveling roll 12, the ratchet plate 252 moves upwardly with the plunger and acts through the pawl 248 to impart clockwise swinging movement to the levers 238 and 230 (Fig. 2). As the lever 230 is thus swung, it imparts upward movement to the rack bar 226, which acts to rotate the rod 184 far enough to move the pin 186 into a substantially vertical position and, accordingly, out of operative relation to the plate 190. It will also be understood that as the rod

138 is moved forwardly to straighten the toggle links 134 and 136, the spring 282 acts on the lever 274 to swing it in the direction to hold its downwardly extending arm 280 against the end 5 of the rod 138. As the rod 138 is moved farther forwardly, to operate the lever 146 to cause the fluid motor 130 to be disconnected from the source of pressure fluid, the lever 274 is further 10 swung by the spring 282, and in response to this swinging movement of the lever the adjustable screw 276, carried by the lever, engages and swings an arm 288 which is pivotally connected at 290 to the bracket 242 in the same direction. Formed integral with the arm 288 is a second 15 upwardly extending arm 292 carrying a pin 294 that extends into an elongated slot 296 in the pawl 248. The construction is such that as the arm 288 is swung by the lever 274 the pawl 248 is moved out of engagement with the ratchet 20 plate 252 thus releasing the lever 230 to the action of the spring 258 for reverse swinging movement in a counterclockwise direction (Fig. 2) to lower the rack bar 226 and to rotate the rod 184 reversely to move the pin 186 again into operative relation to the plate 190.

25 From the above description it will be evident that as the leveling roll 12 is elevated in time relation to the first rearward swinging movement of the jack 10 the rod 184 is rotated by power to move the pin 186 into an inoperative position with respect to the plate 190, and that as the fluid motor 130 is disconnected from its source of pressure fluid to cause the roll to be released for downward movement into engagement with the shoe bottom the pawl 248 is moved out of 30 engagement with the ratchet plate 252, thus permitting the spring 258 to swing the lever 230 downwardly in a direction to impart downward movement to the rack bar 226 to move the pin 186 again into operative relation to the plate 190. When the roll is in engagement with the shoe bottom the rod 138 is in its foremost position and the pawl 248 is held out of engagement with the ratchet plate 252. With the rack bar 226 and 35 the plunger 118 thus disconnected, the heightwise position of the plunger may vary in accordance with variations in the heightwise position of the leveling roll 12, as it operates progressively along the bottom of the shoe, without imparting any turning movement to the rod 138. It will 40 be understood that at this time the pin 186 acts by engagement with the plate 190 to limit rearward movement of the jack. After the forepart has been properly leveled, the operator may, by 45 depressing the treadle 172, move the rod 133 rearwardly far enough to release the lever 146 to the action of its spring 180 and simultaneously to release the pawl 248 to the action of its spring-operated pin 250 without moving the 50 toggle links 134, 136 into non-parallel relation. The fluid motor 130 will then raise the plunger 118 to cause the roll 12 to be lifted out of engagement with the shoe bottom and the pin 196 to be moved into an inoperative position with 55 respect to the plate 190. The jack 10 may then be moved rearwardly far enough to position the shank portion of the shoe under the roll 12 with the pin 186 located rearwardly of the plate 190. Release of the treadle 172 will then permit the 60 rod 138 to move forwardly to cause the fluid motor 130 to be disconnected from its source of pressure fluid and the pawl 248 to be moved out of engagement with the ratchet plate 252, the 65 springs 104 and 106 then acting to press the roll 12 down on the shoe bottom, and the spring 70 75

258 acting through the lever 230 and the rack bar 226 to rotate the rod 184 reversely to move the pin 186 into operative relation to the plate 190. As previously pointed out, while operating in the shank portion the extent of forward movement of the jack 10 is limited by engagement of the pin 186 with the rear edge face 192 of the plate 190 when the roll 12 is located nearly at the junction of the forepart and shank portions of the shoe bottom.

In order to take care of variations in length of the forepart and shank portions at the opposite sides of the shoe bottom, the edge faces 188 and 192 of the plate 190 are curved lengthwise of the plate to accommodate such variations in the style of shoe being operated upon, and means is provided for varying the position of the plate 190 relatively to the pin 186 in response to the tipping of the leveling roll 12. As shown, the plate 190 is secured to a member 300, which is removably secured to a slide 302 by means of a binding screw 304 (Figs. 2 and 5). The slide 302 is vertically movable in a guideway 306 in the bracket 262 and is connected by means of a link 308 to the rearwardly extending arm of a bell-crank lever 310 fulcrumed at 312 to the bracket 262 (Fig. 2). The bell-crank lever 310 has a second arm 314 to which there is pivotally connected a forwardly and downwardly extending bar 316. At its forward end the bar 316 is connected by a link 318 to one arm of a bell-crank lever 320 pivotally connected to the frame 84 by means of a shoulder screw 322 (Figs. 2 and 8). The bell-crank lever 320 has an upwardly extending arm 324 carrying a pin 326 to which is connected a spring 328 the opposite end of which is connected to an adjustable hook 330 carried by a plate 332 secured to the frame 84 by the shoulder screw 322 and a cap screw 334 (Fig. 8). Keyed to the previously mentioned shaft 50 is an upwardly and forwardly extending arm 336 (Fig. 6) carrying at its upper end a pin 338 and loosely mounted on the hub portion 340 of the arm 336 is a second upwardly and forwardly extending arm 342 carrying at its upper end a pin 344. The arm 342 is held against movement lengthwise of the hub portion 340 of the arm 336 by means of a collar 346 secured to the hub 340 by a set screw 348. Formed on the opposite side faces of the bar 316 are U-shaped bosses 350, 352 (Fig. 6), the boss 350 being provided with a central recess 354 open at its lower end to receive the pin 338 carried by the arm 336 in response to downward swinging movement of the bar 316 relatively to the arm 314 of the lever 310, and the boss 352 being provided with a central recess 356 open at its upper end to receive the pin 344 carried by the arm 342 in response to upward swinging movement of the bar 316 relatively to the arm 314.

Formed on the arm 336 are segmental gear teeth 358 that mesh with a pinion 360 loosely mounted on a shaft 362 supported by a bracket 364 which is secured to the frame 84 by screws 366. The pinion 360 meshes with a second equal pinion 368 which is loosely mounted on a shaft 370 supported by the bracket 364 in parallel relation to the shaft 362. Engaging the teeth of the pinion 368 are segmental gear teeth 372 formed on the lever 342, the construction being such that, when the shaft 50 is rotated in one direction or the other, equal swinging movements in opposite directions will be imparted to the arms 336 and 342. It will be evident that by connecting the bar 316 alternately to the arms 336 and 342

a movement in the same direction may be imparted to the plate 190 in response to tipping movements of the leveling roll 12 in opposite directions. Thus a single plate 190 may be utilized to limit the extent of rearward and forward swinging movements of the jack when the roll is operating on either the outside or inside margins of the forepart and shank portions of both left and right shoes of the same style. For swinging the bar 316 about its pivotal connection to the lever 310 to connect it to one or the other of the arms 336 and 342 there is provided a hand lever 374 (Fig. 2) pivoted at 376 to the frame and connected by an adjustable link 378 to the bell crank lever 320. When the parts are in the positions shown in Fig. 2, the spring 328 tends to swing the bell-crank lever 320 in a counterclockwise direction and the bar 316 in a clockwise direction, about its pivotal connection to the lever 310, to hold the bar 316 in engagement with the pin 344 in the arm 342 at the lower end of the slot 356 in the bar. Accordingly, as the arm 52 is swung upwardly to tip the roll 12 in the direction to operate upon the inside margin of a left shoe, the plate 190 will be moved downwardly a distance determined by the extent of tipping movement of the roll, and as the arm 52 is swung downwardly to tip the roll for operation upon the outside margin of the forepart or shank of the left shoe the plate 190 would be moved upwardly a distance determined by the extent of tipping movement of the roll in that direction. When it is desired to operate upon a right shoe of the same style the hand lever 374 will be swung downwardly to swing the bell-crank lever 320 in the direction to impart counterclockwise swinging movement to the bar 316 (Fig. 2) about its pivotal connection to the lever 310 until the pin 338 in the arm 336 engages the bar 316 at the upper end of the slot 354 in the bar. It will be understood that as the bar 316 is thus connected to the arm 336, it will be moved out of engagement with the pin 344 to disconnect it from the arm 342, the spring 328 then acting on the bell-crank lever 320 to hold the parts in those positions. Thereafter, as the arm 52 is swung downwardly to tip the roll 12 for operating upon the inside margin of the forepart and shank of the right shoe, downward movement will be imparted to the plate 190, and as the roll 12 is tipped in the opposite direction for operating upon the outside margin of the forepart and shank of the right shoe, the plate 190 will be moved upwardly. By reference to Fig. 2 it will be seen that the hand lever 62 for controlling the direction, extent and speed of tipping movement of the leveling roll 12 carries a pin 380, and formed on the hand lever 374 are spaced lugs 382. When the machine is initially at rest, the hand lever 374 may be swung relatively to the hand lever 362, without interference between the lugs 382 and the pin 380, to connect the bar 316 to one or the other of the arms 336, 342 for operating upon left or right shoes. If the hand lever 374, however, is accidentally left in an intermediate position, with the bar 316 connected to both of the arms 336 and 342, the pin 380 in the hand lever 62 will be located between the lugs 382 on the hand lever 374, and accordingly the hand lever 62 will be locked against swinging movement in either direction to start the tipping of the leveling roll, thus insuring against any danger of damage to the parts. It will of course then be necessary for the operator to swing the hand lever 374 fully into its uppermost or lowermost position to unlock the hand lever 62.

In the operation of the machine, briefly summarized, the operator mounts a last and shoe on the heel pin carried by the heel post 16, adjusts the heel post toward or from the toe post for the size of shoe to be operated upon, rotates the hand wheel 220 to vary the position of the block 203 relatively to the block 214 for the style of the shoe and, by means of the hand lever 374, connects the bar 316 to the appropriate arm 336, 342 for operating upon either a left or a right shoe. Then by rearward swinging movement of the hand lever 60, the operator causes the jack 10 to be swung rearwardly to bring the toe end of the shoe under the leveling roll 12. As the jack is thus swung the rod 138 is moved forwardly by the spring 139 to swing the toggle links 134, 136 into substantially parallel relation, thus further compressing the spring of the control valve 132 to cause the pressure of the operating fluid to be increased. As the pressure of the operating fluid is increased, the leveling roll 12 is raised by the fluid motor 130 into a position higher than it occupies in operating upon a shoe. In the continued forward movement of the rod 138 the lever 146 is swung, by engagement of the collar 140 on the rod with the collar 142 to which the arm 144 of the lever 146 is pivotally connected, against the resistance of the spring 188 in the direction to impart downward movement to the valve stem 148, thus closing the valve and disconnecting the fluid motor 130 from the source of pressure fluid. This releases the roll 12 and the holder 30 to the action of the springs 104 and 106, the roll being swung downwardly to engage the shoe initially upon the bottom face of its toe end. Thereafter, the operator may, by movement of the hand levers 60, 62, cause the jack to be swung rearwardly and forwardly beneath the leveling roll, the limit of the rearward movement of the jack with the leveling roll in a horizontal position or tipped any desired angle being determined by engagement of the pin 186 with the edge face 188 of the plate 190 each time when the roll is located substantially at the junction of the forepart and shank portions. After the forepart of the shoe bottom has been properly leveled, the operator will depress the treadle 172 to cause the leveling roll to be lifted from engagement with the shoe and the pin 186 to be moved into an inoperative position relatively to the plate 190, and will, by movement of the hand lever 60, cause the jack to be moved rearwardly to bring the shank portion of the shoe under the leveling roll. He will then release the treadle 172, whereupon the roll 12 will again be pressed yieldingly down upon the shoe bottom and the pin 186 moved into operative relation to the plate 190. Then, by movement of the hand levers 60 and 62 the operator will cause the roll to operate progressively along the bottom of the shank portion of the shoe, the limit of forward movement of the jack being determined by engagement of the pin 186 with the edge face 192 of the plate 190 each time when the leveling roll is located nearly at the junction of the shank and forepart; that is, in such relation to the ball line as to cause the roll to level the sole up to that line without obliterating it. At the end of the shank-leveling operation the operator will again depress the treadle 172 to permit the jack to be swung forwardly beyond the position determined by engagement of the pin 186 with the edge face 192 of the plate 190, the jack being then swung forwardly to its ini-

tial position for the removal of the last and shoe.

Having described the invention, what I claim as new and desire to secure by Letters Patent of the United States is:

5. 1. In a leveling machine, a shoe support, a leveling tool, means for effecting relative movement of the shoe support and said leveling tool in directions lengthwise of a shoe on the support to cause the tool to operate progressively along either the forepart or the shank portions of the shoe bottom, and automatic means for terminating said relative movement each time in the operation of the machine when the tool is located nearly at the junction of the forepart and shank portions of the shoe bottom.
10. 2. In a leveling machine, a shoe support, a leveling tool, means for moving said shoe support in opposite directions lengthwise of a shoe thereon to cause the leveling tool to operate progressively along the shoe bottom, and means for automatically terminating the movement of the shoe support in either direction each time in the operation of the machine when the leveling tool is located nearly at the junction of the forepart and shank portions of the shoe bottom.
15. 3. In a leveling machine, a leveling roll, a shoe support mounted to swing rearwardly and forwardly beneath said leveling roll to cause the roll to operate progressively along the bottom of a shoe on said support, means for imparting to the shoe support its rearward and forward swinging movements, and means arranged to prevent swinging movement of the support relatively to the roll in either a rearward or a forward direction beyond a position in which the roll is located on the shoe in predetermined relation to the ball line of the shoe.
20. 4. In a leveling machine, a leveling roll, a shoe support mounted to swing rearwardly and forwardly beneath said leveling roll to cause the roll to operate progressively along the bottom of a shoe on said support, means for imparting to the shoe support its rearward and forward swinging movements, and means for limiting the extent of swinging movement of the support in a rearward direction in operating upon the forepart and for limiting the extent of swinging movement of the support in a forward direction in operating in the shank to cause the support to come to a stop each time in its swinging movement when the roll is located nearly at the junction of the forepart and shank portions of the shoe bottom.
25. 5. In a leveling machine, a leveling roll, a shoe support, power-operated means continuously under manual control for imparting to said support swinging movements of different extents in opposite directions at the will of the operator to cause the leveling roll to operate along the bottom of the forepart and shank portions of a shoe on said support, and means for limiting the extent of swinging movement of the support in one direction in operating upon either the forepart or shank to prevent movement of the support relatively to the roll beyond a position in which the roll is in engagement with the shoe bottom nearly at the junction of the forepart and shank portions.
30. 6. In a leveling machine, a leveling roll, a shoe support, means for moving the support relatively to the roll in opposite directions lengthwise of a shoe on said support to cause the roll to operate progressively along the bottom of the shoe, means for pressing the roll yieldingly upon the shoe bottom, means for preventing movement of the sup-

port in one direction beyond a position in which the roll is located substantially at the junction of the forepart and shank and for preventing movement of the support in the opposite direction beyond a position in which the roll is nearly in the same location on the shoe, and operator-controlled means for lifting the roll from engagement with the shoe and for rendering said last-named means inoperative at will.

7. In a leveling machine, a leveling roll, a shoe support, means for moving said shoe support in opposite directions lengthwise of a shoe thereon to cause the leveling roll to operate progressively along the bottom of the forepart of the shoe, means for pressing said leveling roll yieldingly down on the shoe bottom, means for imparting to the leveling roll tipping movements in opposite directions laterally of the shoe to cause the roll to operate along the opposite sides of the forepart, and means for limiting the movement of the support in one direction to cause the support to come to a stop when the roll is located substantially at the junction of the forepart and shank portions of the shoe bottom, said last-named means being constructed to vary the extent of movement of the support in that direction in response to the tipping of the leveling roll in accordance with variations in length of the forepart at the opposite sides of the bottom of the shoe.

8. In a leveling machine, a leveling roll, a shoe support, means for moving the shoe support in opposite directions lengthwise of a shoe thereon to cause the roll to operate along the bottom of the shank portion of the shoe, means for pressing the roll yieldingly upon the shoe bottom, means for imparting to the roll tipping movements laterally of the shoe to cause the roll to operate along the opposite sides of the shank portion of the shoe bottom, and means for limiting the movement of the support in one direction to cause the support to come to a stop when the roll is located nearly at the junction of the shank and forepart, said last-named means being constructed to vary the extent of movement of the support in that direction in response to the tipping of the leveling roll in accordance with variations in the length of the shank at opposite sides of the shoe bottom.

9. In a leveling machine, a leveling roll, a shoe support mounted to swing rearwardly and forwardly beneath said leveling roll to cause the roll to operate along the bottom of the forepart and shank portions of a shoe on said support, means for imparting to said support its rearward and forward swinging movements, means for pressing the roll yieldingly upon the shoe bottom, means for imparting to the roll tipping movements laterally of the shoe to cause the roll to operate along the opposite sides of the shoe bottom, and means for limiting the extent of rearward swinging movement of the support in operating on the forepart to prevent movement of the support beyond a position in which the roll is located substantially at the junction of the forepart and shank and for also limiting the forward movement of the support in operating in the shank beyond a position in which the roll is nearly in the same location on the shoe, said last-named means being constructed to vary the extent of rearward and forward swinging movements of the support in response to the tipping of the roll in accordance with variations in the lengths of the forepart and shank portions at the opposite sides of the shoe bottom.

10. In a leveling machine, a leveling roll, a shoe support mounted to swing rearwardly and forwardly beneath said leveling roll to cause the roll to operate progressively along the bottom of a shoe on said support, said support having heel and toe posts relatively adjustable to accommodate shoes of different sizes, means for imparting to said support its rearward and forward swinging movements, and means for limiting the extent of swinging movement of the support in a rearward direction in operating on the forepart and in a forward direction in operating in the shank to prevent movement of the support beyond a position in which the roll is located on the shoe in predetermined relation to the ball line of the shoe, said last-named means being constructed to vary the extent of said rearward and forward swinging movements in accordance with variations in the relative positions of the heel and toe posts to maintain the relationship between said position and the ball line substantially constant.

11. In a leveling machine, a leveling roll, a shoe support mounted for rearward and forward swinging movements to cause the roll to operate along the bottom of the forepart and shank portions of a shoe on said support, means for imparting to the support its rearward and forward swinging movements, and means for limiting the swinging movement of the support in a rearward direction in operating on the forepart and in a forward direction in operating in the shank to cause said support to come to a stop each time in its swinging movement when the roll is located on the shoe in predetermined relation to the ball line of the shoe, said last-named means being adjustable to vary proportionately the extents of said rearward and forward swinging movements in accordance with variations in length of the forepart and shank portions of shoes of different styles.

12. In a leveling machine, a shoe support, a leveling roll, means for moving said shoe support in directions lengthwise of a shoe thereon to cause the leveling roll to operate progressively along the bottom of the forepart and shank portions of the shoe, spring means for pressing the leveling roll upon the bottom of the shoe, operator-controlled means for moving the leveling roll against the resistance of said spring means heightwise of the shoe into an elevated position and for releasing it for downward movement into engagement with the shoe bottom, means for preventing movement of the shoe support in either direction lengthwise of the shoe beyond a position in which the leveling roll is located in predetermined relation to the ball line of the shoe, and means for rendering said last-named means inoperative in response to movement of the leveling roll into an elevated position and again operative in response to downward movement of the leveling roll into engagement with the bottom of the shoe.

13. In a leveling machine, a leveling roll, a shoe support, means for moving said support in opposite directions lengthwise of a shoe thereon to cause the roll to operate along the bottom of the forepart and shank portions of the shoe, spring means for pressing the roll yieldingly upon the shoe bottom, means enabling the operator at will to lift the roll against the resistance of said spring means from engagement with the shoe, a stop movable with said shoe support, a member having formed thereon spaced shoulders one of which is arranged by engagement with said mov-

able stop to limit movement of the support in one direction in operating on the forepart to cause the support to come to a stop when the roll is located substantially at the junction of the forepart and shank and the other shoulder of which is arranged by engagement with the movable stop to limit movement of the support in the opposite direction in operating in the shank to cause the support to come to a stop when the roll is nearly in the same location, and means for moving said movable stop out of operative relation to either one of said shoulders in response to movement of the roll out of engagement with the shoe to permit movement of the support beyond the position determined by that shoulder.

14. In a leveling machine, a leveling roll, a shoe support mounted to move rearwardly and forwardly beneath said leveling roll to cause the roll to operate progressively along the shoe bottom, an abutment, a stop movable with said support and arranged by engagement with said abutment to prevent movement of the support in one direction beyond a position in which the roll is located in predetermined relation to the ball line of the shoe, and means for effecting a relative movement of said stop and abutment at will to permit movement of the support beyond the position determined by engagement of the stop with said abutment.

15. In a leveling machine, a leveling roll, a shoe support movable in opposite directions lengthwise of a shoe thereon to cause said roll to operate progressively along the shoe bottom, an abutment, a stop movable with said support and arranged by engagement with the opposite edge faces of said abutment to prevent movement of the support in opposite directions beyond a position in which the roll is located in predetermined relation to the ball line of the shoe, and means enabling the operator at will to move said stop out of operative relation to said abutment to permit movement of the support in either direction beyond the position determined by engagement of said stop with said abutment.

16. In a leveling machine, a leveling roll, a shoe support movable in directions lengthwise of a shoe thereon to cause said roll to operate progressively along the shoe bottom, spring means for pressing said roll yieldingly upon the shoe bottom, a fluid-operated member for lifting said roll out of engagement with the shoe, an abutment, a stop movable with said support and arranged by engagement with said abutment to prevent movement of the support in one direction beyond a position in which the roll is located in predetermined relation to the ball line of the shoe, and mechanism arranged to be connected to said fluid-operated member at will for moving said stop out of operative relation to said abutment.

17. In a leveling machine, a leveling roll, a shoe support, means for moving the shoe support in opposite directions lengthwise of a shoe thereon to cause the roll to operate along the bottom of the shoe, spring means for pressing the leveling roll yieldingly upon the shoe bottom, operator-controlled means for lifting the roll against the resistance of said spring means from engagement with the shoe and then to release it to the action of said spring means at will, a stop movable with the shoe support, a member having spaced shoulders formed thereon arranged by engagement with said movable stop to limit movement of the shoe support in opposite directions lengthwise of the shoe, means for moving said

movable stop out of operative relation to either one of said shoulders in response to movement of the leveling roll out of engagement with the shoe bottom to permit movement of the shoe support beyond the position determined by that shoulder and for moving the movable stop into operative relation to the other shoulder in response to downward movement of the roll into engagement with the bottom of the shoe, and a lost-motion connection between said support and the movable stop arranged to permit a relative movement between the support and said movable stop of sufficient extent to cause the support to come to a stop with the leveling roll located in predetermined relation to the ball line of the shoe by engagement of the movable stop with either one of said shoulders.

18. In a leveling machine, a leveling roll, a shoe support mounted to swing rearwardly and forwardly beneath said leveling roll to cause the roll to operate progressively along the bottom of the shank portion of a shoe on said support, means for imparting to the support its rearward and forward swinging movements, means for imparting to the leveling roll tipping movements in opposite directions laterally of the shoe to cause the roll to operate upon the opposite sides of the bottom of the shank, and means for limiting the forward movement of the support to cause it to come to a stop when the roll is located nearly at the junction of the shank and forepart, said means comprising a stop movable with the support, and a plate for engaging the stop, said plate being movable relatively to the stop in opposite directions in response to the tipping of the leveling roll in opposite directions and being so shaped as to vary the limit of forward swinging movement of the support in accordance with variations in length of the shank at the opposite sides of the shoe bottom.

19. In a leveling machine, a leveling roll, a shoe support mounted to swing rearwardly and forwardly beneath said leveling roll to cause the roll to operate progressively along the bottom of the forepart of a shoe on the support, means for imparting to the support its rearward and forward swinging movements, means for imparting to the leveling roll tipping movements in opposite directions laterally of the shoe to cause the roll to operate upon the opposite sides of the bottom of the forepart, and means for limiting the rearward movement of the support to cause it to come to a stop when the roll is located substantially at the junction of the forepart and shank, said means comprising a stop movable with the support, and a plate for engaging the stop, said plate being movable relatively to the stop in opposite directions in response to the tipping of the leveling roll in opposite directions and being so shaped as to vary the limit of rearward swinging movement of the support in accordance with variations in length of the forepart at the opposite sides of the shoe bottom.

20. In a leveling machine, a leveling roll, a shoe support mounted to move rearwardly and forwardly beneath said leveling roll to cause the roll to operate progressively along the bottom of the forepart of a shoe on said support, means for imparting to said support its rearward and forward movements, means for imparting to the leveling roll tipping movements of different extent in opposite directions laterally of the shoe to cause the roll to operate upon opposite sides of the bottom of the forepart, a stop movable with said support, a plate arranged by engage-

ment with said stop to limit rearward movement of the support beyond a position in which the leveling roll is in engagement with the bottom of the shoe substantially at the junction of the forepart and shank, said plate being movable relatively to the stop in opposite directions in response to the tipping of the roll in opposite directions and being so shaped as to vary the limit of rearward movement of the support in accordance with variations in length of the forepart at the opposite sides of the shoe bottom, and connections between said roll-tipping means and the plate for controlling the movements of the plate relatively to the stop in accordance with the direction and extent of tipping movement imparted to the roll.

21. In a leveling machine, a leveling roll, a shoe support mounted to move rearwardly and forwardly beneath said leveling roll to cause the roll to operate progressively along the bottom of the shank portion of a shoe on said support, means for imparting to said support its rearward and forward movements, means for imparting to the leveling roll tipping movements of different extent in opposite directions laterally of the shoe to cause the roll to operate upon opposite sides of the bottom of the shank, a stop movable with said support, a plate arranged by engagement with said support to limit forward movement of the support beyond a position in which the leveling roll is in engagement with the bottom of the shoe nearly at the junction of the shank and forepart, said plate being movable relatively to the stop in response to the tipping of the leveling roll and being so shaped as to vary the extent of forward movement of the support in accordance with variations in length of the shank at opposite sides of the shoe bottom, and connections between said roll-tipping means and the plate for controlling the movements of the plate relatively to the stop in accordance with the direction and extent of tipping movement imparted to the roll.

22. In a leveling machine, a leveling roll, a shoe support mounted to swing rearwardly and forwardly beneath said roll to cause the roll to operate along the bottom of the forepart of a shoe on said support, means for imparting to said support its rearward and forward swinging movements, means for tipping the leveling roll in opposite directions laterally of the shoe to cause the roll to operate upon opposite sides of the bottom of the forepart, a stop movable with said support, a plate arranged by engagement with said stop to limit rearward movement of the support beyond a position in which the roll is located substantially at the junction of the forepart and shank, said plate being movable in opposite directions in response to tipping movements of the roll in opposite directions and being so shaped as to vary the extent of rearward movement of the support in accordance with variations in length of the forepart at opposite sides of the shoe bottom, and connections between said roll-tipping means and the plate for controlling the movements of the plate relatively to said stop, said connections being adjustable to cause the plate to be moved in the same direction in operating upon either the inside or the outside marginal portions of the bottoms of the foreparts of left and right shoes.

23. In a leveling machine, a leveling roll, a shoe support mounted to swing rearwardly and forwardly beneath said roll to cause the roll to operate along the bottom of the shank portion of

a shoe on said support, means for imparting to said support its rearward and forward swinging movements, means for tipping the leveling roll in opposite directions laterally of the shoe to cause the roll to operate upon opposite sides of the bottom of the shank, a stop movable with said support, a plate arranged by engagement with said stop to limit forward movement of the support beyond the position in which the roll is located nearly at the junction of the shank and forepart, said plate being movable in opposite directions in response to tipping movement of the roll in opposite directions and being so shaped as to vary the extent of forward movement of the support in accordance with variations in length of the shank at opposite sides of the shoe bottom, and connections between said roll-tipping means and the plate for controlling the movements of the plate relatively to said stop, said connections being adjustable to cause the plate to be moved in one direction in operating upon the inside marginal portions and in the opposite direction in operating upon the outside marginal portions of the bottoms of the shanks of both left and right shoes.

24. In a leveling machine, the combination with a leveling roll and a shoe support relatively movable lengthwise of a shoe on the support to cause the leveling roll to operate progressively along the shoe bottom, of power-operated means for tipping the leveling roll in opposite directions laterally of the shoe, means for automatically terminating the relative movement of the shoe support and the leveling roll each time in the operation of the machine when the leveling roll is located in predetermined relation to the ball line of the shoe, said means comprising a member movable in opposite directions in response to relative movement of the support and leveling roll in opposite directions and an abutment arranged by engagement with said member to limit the extent of said relative movements of the support and leveling roll, said abutment being so shaped as to vary the extent of said relative movements in accordance with the variations in length of the forepart and shank at opposite sides of the shoe bottom, connections between the abutment and said power-operated means for moving the abutment in opposite directions in response to tipping movements of the leveling roll in opposite directions, and means for adjusting said connections to cause the abutment to be moved in one direction in operating upon the inside marginal portions and in the opposite direction in operating upon the outside marginal portions of the bottoms of both left and right shoes.

25. In a leveling machine, a leveling roll, a shoe support mounted to swing rearwardly and forwardly beneath said roll to cause the roll to operate progressively along the bottom of a shoe on said support, means for tipping the leveling roll in opposite directions laterally of the shoe, a stop movable with said support, an abutment arranged by engagement with said stop to limit rearward swinging movement of the support beyond a position in which the roll is located substantially at the junction of the forepart and shank portions of the shoe bottom, said abutment being so shaped as to vary the extent of the rearward movement of the support in accordance with variations in length of the forepart at opposite sides of the shoe bottom, and connections between said roll-tipping means and said abutment for moving the abutment relatively to

the stop in opposite directions in response to tipping movements of the leveling roll in opposite directions, said connections comprising a lever connected to said abutment, a pair of arms swingable equal distances in opposite directions in response to the tipping of the leveling roll in either direction, and means for selectively connecting said lever to either one of said arms to cause a movement in one direction to be imparted to said abutment in operating upon the inside margins and a movement in the opposite direction to be imparted to said abutment in operating upon the outside margins of the bottoms of both left and right shoes.

26. In a leveling machine, a leveling roll, a shoe support mounted to swing rearwardly and forwardly beneath said leveling roll to cause the roll to operate progressively along the bottom of a shoe on said support, means for tipping the leveling roll in opposite directions laterally of the shoe to vary its inclination in operating upon the opposite margins of the shoe bottom, a stop movable with said shoe support, a member provided with spaced shoulders one of which is arranged by engagement with said stop to limit rearward movement of the support when the roll is located substantially at the junction of the forepart and shank and the other shoulder of which is arranged by engagement with said stop to limit forward movement of the support when the roll is nearly in the same location on the shoe bottom, said shoulders being so shaped as to vary the limits of rearward and forward movements of the support in accordance with variations in length of the forepart and shank portions at the opposite sides of the shoe bottom, and connections between said roll-tipping means and said member for moving the member relatively to the stop in opposite directions in response to tipping movements of the roll in opposite directions, said connections comprising a lever for thus moving said member and a pair of arms swingable equal distances in opposite directions in response to the tipping of the leveling roll in either direction and arranged to be connected alternately to said lever in operating upon left and right shoes to cause a movement in one direction to be imparted to said member in operating upon the inside marginal portions and a movement in the opposite direction to be imparted to said member in operating upon the outside marginal portions of the bottoms of both left and right shoes.

27. In a leveling machine, a leveling roll, a shoe support mounted to swing rearwardly and forwardly beneath said leveling roll to cause the roll to operate progressively along the bottom of a shoe on the support, said support comprising a toe post and a heel post adjustable toward and from said toe post to accommodate shoes of different sizes, and means for preventing swinging movement of the support in a rearward direction beyond a position in which the leveling roll is located substantially at the junction of the forepart and shank portions of the shoe bottom, said means being adjustable in response to adjustment of the heel post to vary the extent of said rearward swinging movement in accordance with variations in length of the foreparts of shoes of different sizes.

28. In a leveling machine, a leveling roll, a shoe support mounted to swing rearwardly and forwardly beneath said leveling roll to cause the roll to operate progressively along the bottom of a shoe on the support, said support comprising

a toe post and a heel post adjustable toward and from said toe post to accommodate shoes of different sizes, and means for preventing swinging movement of the support in a rearward direction beyond a position in which the leveling roll is located substantially at the junction of the forepart and shank portions of the shoe bottom, said means comprising an abutment, a stop movable with the shoe support and arranged by engagement with said abutment to limit the extent of rearward movement of the shoe support, and connections between said movable stop and the shoe support for varying the position of the movable stop relatively to said abutment by adjustment of the heel post in accordance with variations in length of shoes of different sizes.

29. In a leveling machine, a leveling roll, a shoe support mounted to swing rearwardly and forwardly beneath said leveling roll to cause the roll to operate progressively along the bottom of a shoe on the support, said support comprising a toe post and a heel post adjustable toward and from said toe post to accommodate shoes of different sizes, mechanism for preventing swinging movement of the support in a rearward direction beyond a position in which the leveling roll is located substantially at the junction of the forepart and shank portions of the shoe bottom, and means operable for adjusting said mechanism in response to the adjustment of the heel post to vary the extent of said rearward swinging movement in accordance with variations in length of the foreparts of shoes of different sizes and styles.

30. In a leveling machine, a leveling roll, a shoe support mounted to swing rearwardly and forwardly beneath said leveling roll to cause the roll to operate progressively along the bottom of a shoe on the support, said support comprising a toe post and a heel post adjustable toward and from said toe post to accommodate shoes of different sizes, and means for preventing swinging movement of the support in a rearward direction beyond a position in which the leveling roll is located substantially at the junction of the forepart and shank portions of the shoe bottom, said means being adjustable in response to adjustment of the heel post toward or from the toe post to vary the extent of said rearward swinging movement in accordance with variations in length of the foreparts of shoes of different sizes and being also adjustable independently of the heel post to vary the extent of rearward swinging movement of the shoe support in accordance with variations in length of the foreparts of shoes of different styles.

31. In a leveling machine, a leveling roll, a shoe support mounted for rearward and forward swinging movement beneath said leveling roll to cause the roll to operate progressively along the bottom of a shoe on said support, a stop movable with said support, an abutment arranged by engagement with said stop to prevent rearward swinging movement of the support beyond a position in which the roll is located substantially at the junction of the forepart and shank portions of the shoe bottom, and connections between said stop and the shoe support adjustable to cause the stop to be moved at different rates of speed to vary the extent of rearward swinging movement of the support by engagement of the stop with said abutment in accordance with variations in length of the foreparts of shoes of different styles.
